UNITED STATES PATENT OFFICE

WALTER J. ELLIS, OF INDIANAPOLIS, INDIANA

SUSPENDERS

Application filed December 3, 1931. Serial No. 578,811.

This invention relates to suspenders of the invisible type described in my allowed application, filed November 5, 1930, Serial No. 493,634, Patent No. 1,839,143.

Ordinarily, where the button tabs of suspenders project through openings in the shirt, even though the openings are reinforced, the metal bars which secure the button tabs to the shirt are prone to fray and tear the ends of the openings. To overcome this objection, my present invention provides a front detachable metal bar which may be applied after the button tabs are passed through the openings so that no part of the metal will strike against the openings in the shirt to mutilate the same.

A further object of the invention is to provide an improved anchoring clip in three pieces, two of the pieces having interfitting hooks which cooperate in receiving the spring legs of a catch which removably unites the anchoring clip as a unit assembly to the shirt.

A still further object is to provide an improved anchoring clamp for suspenders' tabs of simple construction and which may be easily applied and, when applied, will be held firmly in proper position.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

Figure 1 is a perspective view showing the manner of applying my improved invisible suspenders to a shirt,

Fig. 2 is an enlarged view of one of the button tabs and anchoring clip, looking from the outside of the shirt,

Fig. 3 is a view similar to Fig. 2 but looking from the inside of the shirt,

Fig. 4 is a longitudinal sectional view taken on the line 4-4 of Fig. 2,

Fig. 5 is a cross sectional view taken on the line 5-5 of Fig. 2,

Fig. 6 is a detail perspective view showing

the parts of the anchoring clip disassembled.

Referring now to the drawing in which like characters of reference designate similar parts in the various views, 10 designates a shirt and 11 suspenders of the invisible type, the shoulder straps of which are engaged through loops 12 sewed inside the shoulders of the shirt. The suspenders are equipped with the usual button tabs 13 which are passed outwardly through slits 14, formed in the shirt, to engage the suspender buttons.

In order to anchor the suspenders to the shirt at the slits 14 and prevent the shirt creeping to an uncomfortable position, I provide an anchoring clip, best shown in perspective in Fig. 6, comprising a back piece 15 having the upper end 16 disposed at an angle to the axis of the back piece and having struck from said upper end a pair of lateral tabs 17 on each side thereof which may be bent over the suspenders. The back piece is provided with a pair of long lateral tabs or bars 18 which are disposed in alinement and project from opposite sides of the back piece to engage the inside of the shirt, above the slit 14, as shown in Fig. 3. Moreover, the back piece is further provided on the front side thereof and near the bottom thereof with a pair of hooks 19 which extend over the front face of the back piece and have their extreme ends beveled, as shown at 20.

A front piece 21 is also provided, the same having, at the top, a pair of laterally extending tabs or bars 22 which are of approximately the same length as the bars 18 and are adapted to engage the front of the shirt just below said bars 18, as best shown in Fig. 2. The bars 18 and 22 coact in clamping the shirt between them and preventing creeping of the shirt. The front piece 21 is provided with hooks 23 struck from the blank and extending oppositely to the hooks 19. The ends of the hooks 23 are beveled, as shown at 24, in an opposite direction from the ends of the hooks 19, the beveled ends of both hooks being adapted to meet and form a continuous eye, as best shown in Fig. 5, when the front piece is applied to the back piece with the hooks 19 of the back piece extending through

the openings 25 from which the hooks of the front piece are struck.

For removably uniting the front piece to the back piece, I provide a substantially U-shaped spring clamp or catch 26, the bight of which is bowed downwardly, as shown in Fig. 4, and engaged in an arcuate loop 28 struck from the top edge of the front piece. The legs of the catch are provided with

10 spring eyes 29, near the loop, and also the legs are terminally provided with eyes 30 which latter eyes may be grasped by the operators fingers to press the legs toward each other, as best shown in Fig. 6, to pass into the hooks 23 of the front piece and allow the front piece to be removed or applied to the back piece.

15 The loop 28 prevents turning of the catch on the front piece so that the legs of the catch are always properly positioned to slide along the front piece when the front piece is being applied or removed from the back piece. It will also be observed that the back piece is provided at the bottom with a pair of outstanding tabs 31, the purpose of which is to provide stops against which the legs of the catch engage and are thereby limited in outward movement. The hooks 23 of the front piece limit inward movement of the legs toward each other.

20 In operation, let us assume that the anchoring clip is applied as shown in Fig. 2 and it is desired to detach the clip from the shirt. It is simply necessary to press the eyes 30 of

25 the catch toward each other so that the legs pass from the hooks 19 of the back piece into the hooks 23 of the front piece, as shown in Fig. 6. Thereupon the front piece may be lifted bodily outwardly from the back piece while the legs are held pressed together.

30 Upon release, the legs spring outwardly against the stops 31 to inoperative position. Thereupon the button tabs 13 may be detached from the suspender buttons and the suspenders applied to a clean shirt.

45 From the above description it is thought that the construction and operation of my invention will be fully understood without further explanation.

50 What is claimed is,

1. Suspenders comprising straps terminating in button-engaging tabs adapted to be passed outwardly through slits in a shirt worn over the suspenders, and clips on the tabs for anchoring the suspenders to the shirt, at said slits, each comprising a back piece fixed to the tab and a front piece removably secured to the back piece.

55 2. Suspenders comprising straps terminating in button-engaging tabs adapted to be passed outwardly through slits in a shirt worn over the suspenders, a back piece permanently secured to each tab and having hooks on the front face, a front piece having openings through which said hooks project and pro-

vided with hooks at the ends of said openings turned toward the first-named hooks, and a U-shaped catch carried by the front piece having spring legs engageable in the hooks of the back piece to assemble the front piece and the back piece as a unit and engageable in the hooks of the front piece to permit disengagement of the front piece bodily from the back piece.

3. Suspenders comprising straps terminating in button-engaging tabs adapted to be passed outwardly through slits in a shirt worn over the suspenders, a back piece carried by each tab having outwardly extending alined arms adapted to engage the back of the shirt near the corresponding slit, a front piece having alined arms adapted to engage the front of the shirt near said slit, said arms binding the shirt between them, said front piece having hooks struck therefrom provided with beveled edges, said back piece having hooks struck therefrom engageable through openings formed in the front piece and having beveled edges to mate with the beveled edges of the hooks of the front piece, the hooks of the front piece and the back piece coacting in forming eyes when the front piece is assembled with the back piece, and an inverted U-shaped spring catch nonrotatably mounted on the front piece and having legs engaged in said eyes to detachably mount the front piece upon the back piece.

In testimony whereof I affix my signature.

WALTER J. ELLIS.
